FIG. 2.

Inventor
A. Cruickshank

By Fred Grotewich Attorneys

UNITED STATES PATENT OFFICE.

ALEXANDER CRUICKSHANK, OF CLAYBURN, BRITISH COLUMBIA, CANADA.

PLIERS.

1,426,553.

specification of Letters Patent. Patented Aug. 22, 1922.

Application filed July 11, 1921. Serial No. 483,884.

To all whom it may concern:

Be it known that I, ALEXANDER CRUICKSHANK, a citizen of the Dominion of Canada, residing at Clayburn, in the Province of 5 British Columbia, Canada, have invented certain new and useful Improvements in Pliers, of which the following is a specification.

This invention relates to a pair of pliers 10 having provision enabling them to effectively serve the purposes of a wrench.

The invention is particularly described in the following specification, reference being made to the drawings by which it is 15 accompanied, in which:

Fig. 1 is a side view of the pliers with the jaw securing pawl in the retaining position, the dot and dash lines showing the release position of the pawl, and

20 Fig. 2 is a plan of the same.

In these drawings 2, 3 represent the opposed plier members which are pivotally connected together by the screw or rivet 4, and the jaws of which are serrated as 25 at 5, to afford an efficient hold.

Concentric with the pivot 4 one edge of the member 3 is notched as at 6 with a series of teeth adapted to receive the end 7 of a securing pawl pivoted at 8 to the 30 adjacent portion of the other member 2.

This pawl 7 has a portion 9 projecting from the side opposite its pivot 8 and having a resilient tendency toward the edge of 3. This portion 9 has a projection 10 from 35 its end which is grooved as shown in Figure 2 and engages the edge of the handle portion of 2 (see dotted lines Figure 1) and retains the pawl in or out of holding engagement with the notches 6 of the member 3, according as it is on one side or the 40 other of the handle member 2.

Although for purposes of illustration the pawl notches 6 are shown as coarsely pitched they may be of any size, consistent with 45 strength that will serve the requirements of the graduation in the jaw opening of the pliers.

The pliers may thus be set to any desired width of opening within their scope, while 50 the pawl 7 is clear of the notches 6, and the pawl be then moved into engagement

with the notches to retain the jaws in the distance apart to which they have been set. The pliers may then be used as a wrench without the requirement of having to grip 55 the handle members together.

It will be noted that the addition of this securing means to the pliers does not interfere with their free use as such.

The use of such pliers for holding the 60 head of a bolt while the nut is being screwed on or off, or for tightening a nut on the bolt is growing in favor, as the tool is a convenient one for this purpose. The addition set forth in the foregoing renders the pliers 65 more serviceable in such use.

Having now particularly described my invention, I hereby declare that what I claim as new and desire to be protected in by Letters Patent, is:

70

1. The combination with a pair of pliers, the handle and jaw members of which are pivotally connected together, a pawl pivotally mounted on one of the plier members the end of which pawl is designed 75 to enter into engagement with one of a series of notches formed on the other plier member concentric with the pivot about which the plier members move, said pawl having a resilient arm provided with a grooved end 80 adapted to spring over the edge of the handle of the plier member on which said pawl is pivotally mounted to hold said pawl out of engagement with said notches.

2. The combination with a pair of pliers, 85 the handle and jaw members of which are pivotally connected together, one of said pliers having ratchet teeth, a pawl pivoted to the other plier member and adapted to engage said ratchet teeth to retain the plier 90 members a definite distance apart, the said pawl having a resilient portion with a projection adapted to engage the handle portion of the plier member to which it is pivoted to retain the pawl in or out of holding 95 engagement with the ratchet teeth accordingly as it is desired to retain the plier members a definite distance apart or not.

In witness whereof I have affixed my signature.

ALEXANDER CRUICKSHANK.
